UNITED STATES PATENT OFFICE.

FREDERICK BENZINGER, OF NEW YORK, N. Y., AND HANS EDGAR GRABAU,
OF HOBOKEN, NEW JERSEY.

DESIGN FOR A RULE.

SPECIFICATION forming part of Design No. 19,379, dated October 29, 1889.

Application filed September 26, 1889. Serial No. 325,219. Term of patent 7 years.

To all whom it may concern:

Be it known that we, FREDERICK BENZINGER, of the city, county, and State of New York, a citizen of the United States, and 5 HANS EDGAR GRABAU, of Hoboken, in the county of Hudson and State of New Jersey, a citizen of the German Empire, have invented a certain new and original Design for Rules, of which the following is a specification, reference being had to the accompanying drawing, which shows a perspective view of part of a draftsman's rule showing our design.

The leading feature of our design consists 15 in the convexly-curved longitudinal faces in each side of a draftsman's rule, having a triangular cross-section.

A is the rule, having the three sides B' B² B³.

C is a longitudinal central convexly-curved 20 part on each face of the rule.

E E are longitudinal straight parts on each

face of the rule, and F F are longitudinal shoulders at the inner edges of the straight parts E E.

Having thus described our design, we claim 25 as new and desire to secure by Letters Patent—

A design for a draftsman's rule of triangular cross-section, as herein shown and described, the same consisting of the straight 30 parts E, the convexly-curved longitudinal central part C, and the longitudinal shoulders F on each face of the rule, substantially as set forth.

In testimony that we claim the foregoing as 35 our invention we have signed our names in presence of two subscribing witnesses,

FRED. BENZINGER.
HANS EDGAR GRABAU.
